JOHN H. CONNOR, OF BOSTON, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SHOES.

1,302,995.

Specification of Letters Patent.

Patented May 6, 1919.

Application filed November 30, 1917. Serial No. 204,631.

To all whom it may concern:

Be it known that I, JOHN H. CONNOR, a citizen of the United States, residing at Boston, in the county of Suffolk and State of Massachusetts, have invented certain Improvements in the Manufacture of Shoes, of which the following description, in connection with the accompanying drawings, is a specification, like reference characters on the drawings indicating like parts in the several figures.

This invention relates to the manufacture of shoes and more particularly to an improved method of making shoes of the type commonly termed "turn" shoes and to the novel shoes produced by the practice of this method.

In the manufacture of turn shoes it is a common practice to employ counters which have been previously molded substantially to final shape, previously molded counters being used not only in turn shoes made with what are commonly termed "sewed heel seats" but also in turn shoes having what are usually called "nailed heel seats," sewed heel seats and nailed heel seats representing the two types of turn shoes heretofore manufactured. In turn shoes of the type first named, the margin of the shoe upper is secured to the sole around the heel seat, before the shoe is turned right side out, by a continuation of the sewed seam securing the upper to the sole through the forepart and shank. In turn shoes of the type having nailed heel seats, the sewed seam securing the upper to the sole is terminated substantially at the heel breast line of the sole, the margin of the upper at the heel being lasted over and secured by tacks to the bottom of the counter and to a special heel seat member provided for this purpose after the shoe is turned right side out. Turn shoes of both these types as heretofore made present difficulties in the way of advantageously and properly incorporating previously molded counters in the shoe construction.

An object of the present invention is to provide an improved method of making turn shoes such that previously molded counters may be employed without any of the disadvantages heretofore attendant upon their use, to the end that turn shoes may be made more advantageously and efficiently than was pos-

sible by the methods heretofore practised and with the resulting shoe presenting an improved appearance and fitting better than the turn shoes produced by prior methods.

To this end, the invention consists, in one of its aspects, in sewing a shoe upper inside out to a sole forwardly of a line substantially coincident with the heel breast line of the sole, then lasting the unattached heel end of the shoe upper over into lasted position upon the heel end of the sole and securing it in lasted position thereto by a substantially flat seam prior to turning the shoe right side out and subsequently incorporating a previously molded counter in its proper lateral and longitudinal relative position in the shoe. By reason of the substantially flat seam connecting the upper to the sole at the heel seat it is possible to seat a molded counter more closely and firmly on the sole than where the counter is seated upon the sewing rib of a sewed seat shoe and as a result the shoe upper conforms more accurately to the contour of the counter particularly adjacent to the sole, and the disadvantage heretofore experienced in creating a fullness of upper when the heeling pressure is applied to the shoe is entirely overcome.

As herein illustrated the flat seam which connects the shoe upper to the sole around the heel end is formed by lasting the heel portion of the upper over on the sole before the shoe is turned right side out and then securing it in position with a plurality of metallic fastenings passing through the overlasted upper which lies flat upon the sole and clenched in the sole. As a result of this procedure the heel seat lasting operation may be performed with considerable accuracy and facility since the heel seat is entirely exposed to the workman and the free heel end of the sole is not in his way as was the case when a nailed seat was made by prior methods. Also, a pocket is provided at the heel end of the shoe accurately to receive the heel portion of the "second" last after the shoe is turned. This latter feature is of considerable practical advantage inasmuch as it predetermines the proper relation of the assembled shoe upper on the second last without the exercise of any great care on the part of the workman.

The above and other features of the herein

described method, as well as the novel step products provided by the invention, will be apparent from the following description when considered in connection with the accompanying drawings which illustrate a preferred embodiment of the invention and the novel features will then be defined in the appended claims.

In the drawings,
10 Figure 1 is a perspective view of a shoe showing an assembled shoe upper secured to a sole in accordance with the present invention;

15 Fig. 2 is a perspective view illustrating one manner of incorporating a previously molded counter in a shoe produced by the practice of the invention;

20 Fig. 3 is a perspective view, partly in section, illustrating the shoe in the process of being turned right side out;

25 Fig. 4 is a perspective view of the completed shoe showing the heel portion of the shoe partly in section.

For the purpose of illustration, the invention is herein shown as being practised in conjunction with a method of making turn shoes, involving the use of previously molded counters, known as the Thissell method and which is the subject-matter of pending application Ser. No. 169,018, filed Dec. 28, 1915, 30 owned by the assignee of the present invention.

In carrying out the method of the invention in connection with the Thissell method, 35 a shoe upper comprising an upper 2 and a lining 4, together with the usual box toe is first assembled with the shoe upper inside out, that is, with the lining outside, upon a last 6. A sole 8, shaped substantially to its 40 size in the finished shoe and having the usual shoulder and sewing channel upon its upper surface is also temporarily secured in position on the last bottom. The assembled upper is lasted over on to the sole in the customary manner and then permanently secured to the sole by stitches 10 constituting a sewed seam. This sewed seam 10 extends 45 from a point at substantially the heel breast line on one side of the shoe through the shank, forepart and opposite shank portion to the heel breast line on the opposite side of the shoe. The upper 2 and lining 4 are both secured to the sole 8 by the sewed seam 10, but, preferably, the lining is slit at a 50 point forward of the heel breast line or the termination of the sewed seam, indicated at 5, a distance approximating the length of the counter wings of a previously molded counter so that the lining is left unattached 55 to the sole from this point on one side of the shoe around the heel end to a similar point on the opposite side of the shoe. The lining 4 is left free of attachment to the sole 8 in order to enable a previously molded counter 60 the wings of which invariably extend 65

forwardly of the heel breast line of the shoe to be interposed between the shoe upper 2 and the lining 4, as will hereinafter be described.

Following the permanent attachment of the assembled shoe upper to the sole forwardly of the heel breast line, the margin 12 of the unattached heel end of the upper is lasted over on to the upper or flesh side of the heel end of the sole and permanently secured in overlasted position thereon. This attachment of the upper to the sole is such as to produce a substantially flat seam at the heel seat of the shoe. As herein shown the means which are used for connecting the margin 12 of the upper to the sole 8 are lasting tacks 14 driven through the overlasted margin of the upper from the unfinished side of the upper and through the sole, the tacks being clenched upon the grain side of the sole at the heel by the metal bottom ordinarily provided on the heel seat of the last 6. This manner of attaching the upper to the sole around the heel end of the sole produces a firm and substantially flat heel seat surface, that is, the upper surface of the heel end of the sole does not present an upstanding rib or projecting seam as is the case with a shoe having a sewed heel seat in which the sewed seam is continued around the heel end of the shoe. It is to be noted that the lining 4 is left unattached to the sole around the heel and that the heel end of the upper 2 is permanently attached to the heel end of the sole 8 prior to turning the shoe right side out. By reason of this procedure the heel lasting operation may be performed at a more convenient stage in the production of the shoe under most shoe factory systems than where it is necessary to perform the heel seat lasting operation after the shoe has 105 been turned right side out as with the prior methods of making turn shoes having nailed heel seats. Moreover, the heel end of the shoe is entirely exposed to the workman for the heel seat lasting operation so that this 110 operation may be performed with greater accuracy and facility. With prior heel seat lasting operations which are performed after the shoe is turned, it is necessary for the workman to bend the free heel end of the 115 sole toward the toe of the shoe to expose the heel seat and enable him to last the heel end of the upper over on to the heel seat member, and considerable difficulty is often experienced by the workman not properly 120 securing the overlasted margin of the upper to the sole near the termination of the sewed seam. Unless extreme care is used the bending of the sole to expose the heel seat tends to "start" the inseam at its termination on either side of the shoe. A further advantage obtained by lasting the heel margin of the upper over on to the sole before the shoe is turned right side out is that the heads of the tacks 14 are thereby located in the inter- 130

rior of the shoe and the points of the tacks on the under side of the sole. It has also been found that less fullness and wrinkles are produced in the heel end of the upper 5 adjacent to the sole after it is turned right side out when the upper is lasted over and secured to the sole wrong side out.

Any of the commonly practised methods of incorporating a previously molded coun-

- 10 ter in a turn shoe may be successfully practised in completing the shoe. The illustrated method consists in providing a previously molded counter 18 with a bottom piece 20 which fits inside the counter and
- 15 is secured thereto through its inturned flange. This bottom piece 20 serves to maintain the shape of the counter 18 in the shoe and more especially it prevents the forward ends of the counter where they extend forwardly of the heel breast line of the shoe from spreading outwardly which is detrimental to the appearance and wearing qualities of the shoe. This counter is secured to the sole in the position it assumes in the
- 20 finished shoe by a plurality of tacks, these tacks of course being confined within the area of the heel seat which is back of the heel breast line so as to prevent them from showing on the bottom surface of the sole
- 25 in the finished shoe. By lasting the upper over on to the sole and securing it by tacks, a substantially flat and firm seat is provided to receive the counter 18 with the result that a well-defined rand crease or shoulder along
- 30 the angle between the sole and the upper in the finished shoe is obtained and the upper conforms accurately to the contour of the counter and last, thus making it unnecessary to shrink the upper to the contour of the
- 35 counter by means of a hot iron or similar treatment. Moreover in the operation of attaching the heel to the shoe the heelining pressure has no opportunity to distort or upset the relative positions of the materials
- 40 constituting the heel end of the shoe before the counter is firmly seated on the sole as often occurs when a previously molded counter is seated upon the top of the sewed seam of a turn shoe having a sewed seat. Ac-
- 45 cording to the general practice the forepart of the shoe is first turned as shown in Fig. 3 and then the heel portion of the shoe is turned. In turning the heel portion of the shoe the lining 4, which is not secured to
- 50 the sole 8 about the heel, is first pulled upwardly over the counter 18 in the manner indicated in Fig. 3 which procedure also turns the upper 2 backwardly and upwardly over the counter. After the upper 2 has
- 55 been turned right side out about the counter, the lining 4 is turned in over the inner face of the counter so that the counter is disposed between the upper 2 and the lining 4. The inner face of the counter is preferably
- 60 coated with cement and the lower marginal
- 65 edge of the lining 4 is turned out on to the bottom piece 20 and the usual heel seat and shank member 23 inserted in the shoe. Since the lining 4 is unsecured after the shoe is turned and prior to re-lasting any 70 fullness and wrinkles in the lining may be properly disposed of before the second last is inserted in the shoe. The shoe is then re-lasting in the usual manner by inserting a "second" last. The pocket formed in the 75 heel end of the upper by reason of the upper and sole being attached serves to predetermine the relative position of the last in the shoe and thus insures against the heel end of the upper being too "high" or "low" on 80 the last with a consequent result of producing a misshaped and poor fitting shoe. Subsequent turn shoe making operations are performed on the shoe in the usual manner including the heel seat nailing operation 85 which inserts a series of nails 25 through the margin of the sole, upper, counter and heel seat. The heel seat nails are ordinarily inserted from the outside of the shoe inwardly and clenched on the inside of the 90 shoe and serve to fasten the constituent shoe parts around the heel firmly together. After the heel seat nailing operation the usual heel and sole edge trimming, heelining and finishing operations may be performed in the de- 95 sired manner.

It will be observed that the invention also provides novel step products at different stages in the manufacture of a turn shoe before its completion whether or not the process herein set forth is practised in its entirety. Such a step product comprises a shoe upper inside out, a sole, the upper and the sole being secured together by a sewed seam extending around the forepart 100 and the shank and said upper being overlasted on the heel seat portion of the sole on the side of the sole to which the upper is sewed and secured thereto by tacks and a molded counter seated on the tacked heel 110 seat portion of the sole, a product of this character being fully illustrated in Fig. 2. In another aspect, the invention provides as a novel step product at another stage in the manufacture of a turn shoe, a shoe upper, 115 a sole, the upper and sole being secured together by a sewed seam extending around the forepart and the shank and said member being overlasted on the heel seat portion of the sole on the side of the sole to which the 120 upper is sewed and secured thereto by tacks, a molded counter seated on the tacked heel seat portion of the sole, and fastenings securing the upper and the counter to the sole.

Having described my invention, what I 125 claim as new and desire to secure by Letters Patent of the United States is:—

1. That improvement in the art of making turn shoes which consists in assembling an upper wrong side out and a sole upon a last, 130

4
sewing the upper to the sole forwardly of a line substantially coinciding with the heel breast line of the sole, lasting the heel end of the upper over on to the heel end of the sole and securing it in lasted position by a substantially flat seam prior to turning the shoe right side out and subsequently incorporating a previously molded counter in the shoe and completing the manufacture of the shoe.

10 2. That improvement in the art of making turn shoes which consists in assembling an upper wrong side out and a sole upon a last, sewing the upper to the sole forwardly of a line substantially coincident with the heel breast line of the sole, lasting the heel end of the upper over on to the heel end of the sole prior to turning the shoe right side out and securing it in lasted position by metallic fastenings passing through the margin of the upper and into the sole, and subsequently incorporating a previously molded counter in the shoe.

15 3. That improvement in the art of making turn shoes which consists in assembling an upper wrong side out and a sole upon a last, sewing the upper to the sole forwardly of a line substantially coincident with the heel breast line, lasting the upper over on to the upper side of the heel end of the sole and securing it in lasted position by a substantially flat seam, positioning a molded counter on the sole in the position desired in the finished shoe and attaching it to the sole, with drawing the last and turning the shoe right side out and then completing the manufacture of the shoe.

20 4. That improvement in the art of making turn shoes which consists in assembling an upper and lining wrong side out, together with a sole, upon a last, sewing the upper and lining to the sole forwardly of a line substantially coincident with the heel breast line but leaving the lining unattached to the sole approximately as far forward as the counter wings extend, lasting the heel end of the upper over on to the heel end of the sole and securing it in lasted position by metallic fastenings prior to turning the shoe right side out, and subsequently incorporating a molded counter in the shoe with the body of the counter disposed between the upper and the lining and thereafter completing the manufacture of the shoe.

25 5. That improvement in the art of making turn shoes which consists in assembling an upper and lining wrong side out and a sole upon a last, sewing the upper and lining to the sole forwardly of a line substantially coincident with the heel breast line of the sole but leaving the lining unattached to the sole approximately as far forward of the termination of the inseam as the counter wings extend, lasting the heel end of the upper over on to the heel end of the sole and secur-

ing it in lasted position by metallic fastenings but leaving the lining unattached to the sole, permanently attaching a previously molded counter to the sole and thereafter withdrawing the last and turning the shoe right side out and during the said turning of the shoe disposing the body of the counter between the upper and the lining.

6. That improvement in the art of making turn shoes which consists in assembling an upper and lining wrong side out and a sole upon a last, sewing the upper and lining to the sole forwardly of a line substantially coincident with the heel breast line but leaving the lining unattached to the sole approximately as far forward as the counter wings extend, lasting the upper over on to the heel end of the sole and securing it in lasted position by metallic fastenings, permanently attaching a previously molded counter to the heel end of the sole in the relative position it is to occupy in the finished shoe, turning the shoe right side out and incidentally disposing the counter between the upper and the lining at the heel end of the shoe and then securing the margin of the heel end of the sole, the upper and the counter together and completing the manufacture of the shoe.

7. That improvement in the art of making shoes which consists in providing a sole blank of a shape corresponding substantially to the shape of the sole blank in the finished shoe, assembling an upper and lining wrong side out and a sole upon a last, sewing the upper and lining to the sole forwardly of a line substantially coincident with the heel breast line of the sole but leaving the lining unattached to the sole approximately as far forward of the termination of the inseam as the counter wings extend, lasting the margin of the heel end of the upper over on to the heel end of the sole and securing it in lasted position by metallic fastenings passing through the margin of the upper and the sole and clenched upon the grain side of the sole, the lining being left unattached to the sole, permanently attaching a previously molded counter in final position on the flesh side of the heel end of the sole, and then turning the shoe right side out and incidentally disposing the counter between the upper and the lining.

8. A turn shoe comprising a sole, an upper secured to the sole forwardly of a line substantially coincident with the heel breast line by a seam of single-faced stitches and having its heel end independently secured to the sole by metallic fastenings the points of which are clenched upon the underside of the sole, a heel stiffener independently attached to the sole with metallic fastenings, a heel seat member, and fastenings securing together the margins of the sole, upper, heel stiffener and heel seat member.

9. That improvement in the art of making

turn soles which consists in lasting and sewing an assembled shoe upper around the forepart and shank of a sole, lasting and tacking the shoe upper around the heel seat of the 5 sole to the same side of the sole to which the upper is sewed around the forepart and the shank, locating a molded counter having an inturned flange on the sole with the flange of the counter seated upon the tacked seam, fastening the said counter to the sole and thereafter turning the shoe right side out and completing its manufacture in the usual 10 manner.

10. A step product in the manufacture of 15 a turn shoe comprising a shoe upper inside out, a sole, the upper and the sole being secured together by a sewed seam extending around the forepart and the shank and said upper being overlasted on the heel seat por-

tion of the sole on the side of the sole to 20 which the upper is sewed and secured thereto by tacks, and a molded counter seated on the tacked heel seat portion of the sole.

11. A step product in the manufacture of a turn shoe comprising a shoe upper, a sole, 25 the upper and sole being secured together by a sewed seam extending around the forepart and the shank, the said upper being overlasted on the heel seat portion of the shoe on the side of the sole to which the upper is 30 sewed and secured thereto by tacks, a molded counter seated on the tacked heel seat portion of the sole, and fastenings securing the upper and the counter to the sole.

In testimony whereof I have signed my 35 name to this specification.

JOHN H. CONNOR.
